CLAIM

The ornamental design for the block puzzle, as shown and described.

DESCRIPTION

FIG. 1 is an assembled front view of the block puzzle showing my new design;

FIG. 2 is an exploded front view thereof;

FIG. 3 is an assembled front perspective view thereof;

FIG. 4 is an exploded front perspective view thereof;

FIG. 5 is a front view of a second embodiment of the block puzzle, shown with surface features in dotted lines;

FIG. 6 is a back view of the second embodiment, shown with surface features in dotted lines;

FIG. 7 is a right side view of the first and second embodiments; and,

FIG. 8 is a left side view of the first and second embodiments. The dotted lines are included for the purpose of illustrating surface features that form no part of the claimed design.
